MONEYBAG BANK

Bernard Krebs and Morton Krebs, New York, N. Y.

Application May 9, 1950, Serial No. 9,816

Term of patent 7 years

(Cl. D34—11)

To all whom it may concern:

Be it known that we, Bernard Krebs and Morton Krebs, citizens of the United States, residing at New York city, in the county of Kings and State of New York, have invented a new, original, and ornamental Design for Moneybag Bank, of which the following is a specification, reference being had to the accompanying drawing, forming part thereof.

In the drawing:

Fig. 1 is a front elevational view of a moneybag bank showing our new design;

Fig. 2 is a side elevational view thereof; and

Fig. 3 is a bottom plan view.

The dominant features of our design are shown in solid lines in the drawing.

We claim:

The ornamental design for a moneybag bank, substantially as shown and described.

BERNARD KREBS.
MORTON KREBS.
